MECHANICAL TOY

Arthur W. Swenson, Rockford, Ill.

Application November 30, 1939, Serial No. 306,880

19 Claims. (Cl. 46—129)

The invention relates to mechanical toys and more particularly to those adapted to simulate the motions and appearance of a child skipping rope.

The general object is to provide a toy of the above character which is very realistic in appearance and operation by virtue of the novel construction and manner of actuating the simulated jumping rope and the parts of the toy figure associated therewith.

Another object is to provide for turning the simulated rope and imparting the necessary motions to the toy figure by means of a novel reciprocating actuator.

Still another object is to provide a toy of the type set forth embodying a novel actuating mechanism of such character that a rotatable member, simulating a skipping rope, is rotated by means of a reciprocating actuator, the arrangement also being preferably such that the actuator serves to reciprocate in timed relation a doll or figure, to simulate the jumping motions of a child skipping rope.

A further object is to provide for actuation of the various parts by the intermittent depression of a finger piece.

The invention also resides in the novel structural character of the actuating mechanism which simplifies the toy and contributes to its very low cost of manufacture.

Further objects and advantages of the invention will become apparent as the following description proceeds, taken in connection with the accompanying drawing in which

Figure 1 is a general perspective view of the improved mechanical toy illustrating its manner of use.

Fig. 2 is an enlarged vertical transverse sectional view of the toy.

Fig. 3 is an enlarged fragmentary perspective view of the toy with parts thereof broken away to show the interiorly located actuating mechanism.

While the invention is susceptible of various modifications and alternative constructions, I have shown in the drawing and will herein describe in detail the preferred embodiment, but it is to be understood that I do not intend to limit the invention by such disclosure but aim to cover all modifications and alternative arrangements falling within the spirit and scope of the invention as expressed in the appended claims.

In the exemplary construction, the toy includes a hollow figure 10 suitably shaped and decorated to represent a girl. In brief, the arrangement is

such that when an actuating finger piece 11 is intermittently depressed the figure 10 will jump up and down and at the same time a member 12, simulating a skipping rope, will rotate about the figure, the arms and legs also being moved in timed relation with the rope. In this way, the toy simulates, in a manner very intriguing to a youngster, the appearance and action of a child skipping rope. To vary the operation and add to the fun, the skipping can be speeded up, slowed down, or reversed by correspondingly timing the impulses given to the actuator mechanism through the finger piece 11.

To support the figure 10 for its vertical reciprocation or jumping motion, it is fixed to the upper end (Fig. 3) of an upright actuator bar 14, which projects upwardly through the hollow figure. The upper end 15 of the bar is interlocked with the body of the figure 10 and concealed with the separately formed head 10^a. The bar 14 is located between and guided for vertical reciprocation by a pair of rigid sheet metal strips or uprights 16 having outwardly flared upper end portions 16^a (Fig. 3) connected by a pin 17. The latter projects through a complementary vertical guide slot 18 in the bar 14 forming a pin and slot connection that holds the bar 14 against edge-wise displacement. It will be observed from Fig. 1 that the supporting and actuating mechanisms are disposed between the legs 28 of the figure 10 and thus partially concealed so that the figure appears to be standing naturally on a base or platform 19.

The uprights 16 are stationarily mounted on a suitable base 19 with their lower ends projecting through an aperture 20 (Fig. 2) and bent laterally as indicated at 16^b for attachment to the base as by spot welding.

The simulated rope 12 comprises a piece of wire in the shape of a U having a base 12^a and two arms 12^b projecting laterally from the base at an angle greater than ninety degrees with their end portions 12^c curved inwardly toward each other to bring their ends into alignment immediately adjacent opposite sides of the bars 16 and beneath the legs 28 of the figure when the rope is in vertical position (Fig. 2).

Of particular importance in the present toy is the mechanism by means of which reciprocating motion of the actuator bar 14 is utilized to impart a rotary motion to the rope 12. This mechanism is a very simple and cheap Scotch yoke comprising a horizontal slot 22 in the actuator bar coacting with a crank 21 on the shaft formed by the base 12^a of the rope 12. The crank is

bent from the shaft 12^a which is disposed horizontally and journaled in the ends 16^a of the supporting uprights 16 with the outer ends projecting through vertical slots 23 in the sides of the figure body. As the actuator bar 14 is reciprocated, the crank loop 21 rides back and forth in the slot 22, rotating the rope 12 through a full revolution for each complete reciprocation of the actuator bar. By varying the position of the rope when actuation of the bar 14 is initiated, the rope may be started in either direction.

By virtue of the space between the ends 12^c of the rope, complete and continuous rotation of the rope is permitted without interference by the uprights 16 and the vertical actuator bar 14 (Fig. 2). Because of the flat and compact character of the supporting bars and the reciprocatory character of the actuator, this break in the rope is small, however, and can hardly be seen at all when the rope is rotating rapidly so that it does not detract from the illusion created. Desirably, the side arms of the member 12 are bowed outward, as indicated, so as to conform to the configuration a regular rope assumes in use. The location of the actuator bar 14 between the stationary uprights 16 further adds to the illusion of an animated figure since the movement of the actuator bar when so located can hardly be seen.

Actuation of the bar 14 may be effected in various ways depending on the character of the base 19 which is employed. For example, if the base is arranged to be held in one's hand, provision would be made for reciprocating the bar by the movement of the thumb or other digits of the hand. In the present instance, however, the base is adapted to rest on a horizontal supporting surface during operation of the toy and therefore is constructed as an inverted sheet metal box of generally rectangular shape. The bar 14 is actuated by periodic depression of an operating member 11 which may be engaged conveniently by the forefinger of the user's hand located as shown in Fig. 1. To complete a connection from the finger piece 11 to the actuator bar 14, a second actuator bar 24 underlies the top of the base 19 (Fig. 3) with its rear end 25 projecting through a complementary hole in the end wall at the base and bent downwardly thereby forming a pivotal connection. The forward or free end of the bar 24 is connected to the lower end of the upright actuator bar 14 with a sufficiently loose connection to permit rectilinear movement of the bar 14 and oscillatory movement of the bar 24. For this purpose, the reduced lower end of the bar 14 extends through a registering hole in the forward end of the bar 24 and a transverse pin 26 (Fig. 2) maintains the connection. The finger piece 11 is spot welded to an intermediate portion of the actuator bar 24 adjacent the latter's pivoted end and is exposed through a slot 27 in the top wall of the base 19.

In order to further simulate the appearance of a child skipping rope, movable arms and legs are provided on the figure 10 and arranged to be moved in timed relation with the skipping rope member 12. For this purpose, jointed arms 27 are pivoted at 27^a to the shoulders of the Figure 10. The lower ends of these arms are pivotally connected to the outer end portions of the horizontal shaft 12^a. As the figure 10 moves up and down with the actuator bar 14, the shoulder pivots 27^a are correspondingly raised and lowered. Although the hand pivots remain stationary, the arms are alternately flexed and dis-

Similarly, sheet metal legs 28 are pivoted on a pin 29 fixed between the walls of the skirt portion of the figure 10 and to the actuator bar 14, the pin being extended through complementary vertical slots 30 in the stationary uprights 16. From the front of these legs project integral lugs or abutments 31 (Fig. 3) beneath laterally extending lugs 32 on the uprights 16. As the figure 10 moves upward, the lugs 31 contact the stationary lugs 32 so that the legs 28 are swung rearwardly from the position of Fig. 1 to that of Fig. 3. Then, as the figure 10 descends again, the legs 28 are gravitationally returned to their vertical position, since the lugs 31 move downward away from the lugs 32. The cooperating lugs 31, 32 and pivotal support for the legs are effectually hidden from view beneath the skirt of the figure 10 in the arrangement shown. The crank 21 is angularly positioned relative to the rope 12 so as to be disposed substantially in the plane of the U and project from the shaft 12^a in a direction opposite to the arms 12^b. By virtue of this arrangement, the rope will pass beneath the figure while the bar is approaching and receding from its uppermost position. At this time, the legs 28 will be swung backwardly as shown in Fig. 3. Such timing between the leg and rope movements makes the rope skipping action very realistic.

Operation of the toy is effected by depressing the finger piece 11 periodically and in timed relation to the rotation of the simulated rope 12. Such depression of the finger piece oscillates the bar 24 downward about its pivot at 25 and this bar in turn draws down the vertical actuator bar 14. Motion is thereby simultaneously imparted to the figure 10, the skipping rope member 12, and to the arms and legs 27 and 28. Thus, the figure 10, being fixed to the bar 14, moves down with it while the arms 27 are flexed and the legs 28 are permitted to swing downwardly and forwardly to normal position (from the position of Fig. 3 to that of Fig. 1) all as previously described. As to the skipping rope 12, if the crank loop 21 is slightly forward (as viewed in Fig. 3) of its dead center position then the crank will ride forward in the slot 22 as the bar 14 descends and the rope 12 will rotate in a counterclockwise direction. As the arms of the member 12 reach their overhead position, they swing on at least slightly past dead center due to their momentum. Then, the weight of the free end of the rope, plus the momentum, carries the rope on down in front of the figure 10 to complete a full revolution. In this part of the revolution, the rope 12 becomes in effect the driving member of the mechanism and the crank 21 thrusts the actuator bar 14 upward, the finger piece 11 having been freed by the operator after its initial depression. The operator then redepresses the finger piece and the cycle is repeated as often as desired. Practice of only a minute or two is required to get the rhythm of the device for actuating the finger piece to operate the toy for smooth and continuous rotation of the skipping rope. By gradually varying the periodicity with which the finger piece is actuated, the speed of rotation of the rope can be increased or diminished as desired.

It will be apparent that the rope 12 can be revolved in either direction desired, the controlling factor being the location of the crank loop 21 with respect to dead center when the operation is started. As was previously noted, if the crank is slightly forward of its dead center posi-

tion at the start, the rope will revolve in a counterclockwise direction. Similarly, if the crank is located slightly to the rear of its dead center position, the rope will revolve in the opposite or clockwise direction.

I claim as my invention:

1. In a mechanical toy, the combination of a figure, a vertically reciprocable actuator bar projecting upwardly into the interior of said figure from the bottom thereof, said actuator bar being transversely slotted at a point within the figure, a U-shaped member arranged with the base of the U extending through said slot and rotatable about an axis transverse to the figure, the arms of the U being arranged to turn vertically at the sides of the figure in the manner of a skipping rope, the base portion of the U having an offset crank loop therein engageable with the sides of the slot in the actuator bar, said U-shaped member having a rest position with its arms hanging downwardly, and manually operable means for intermittently drawing the actuator bar downward to swing said U-shaped member from said rest position through a half revolution by the action of said crank and slot connection, the subsequent gravitational descent of the arms of the U to their rest position serving to complete a full revolution for the U-shaped member.

2. In a mechanical toy, the combination of a vertically reciprocable actuator bar in the form of an upstanding sheet metal strip, a hollow figure telescoped over the upper portion of said actuator bar and fixed thereto, a U-shaped member, means rotatably supporting the base portion of said U-shaped member for rotation about an axis passing transversely through the figure, the arms of the U being swingable vertically at the sides of the figure in the manner of a skipping rope, said actuator bar being transversely slotted to receive the base portion of said U-shaped member and the latter having an offset crank loop therein engageable with the walls of said slot to complete therewith a Scotch yoke connection, and manually operable means for reciprocating said actuator bar.

3. In a mechanical toy, the combination of a hollow figure, a vertically reciprocable actuator bar projecting upwardly into said figure and supporting the latter, a slot in said actuator bar within the figure, a horizontal rotatable shaft extending through the slot and said figure, vertically swingable arms on the ends of said shaft exteriorly of said figure and shaped to simulate a jumping rope, and a crank on said shaft engageable with the sides of said slot to form therewith a Scotch yoke drive mechanism for rotating said shaft and arms during reciprocation of said bar.

4. In a mechanical toy, the combination of a figure, a driven member representing a skipping rope carried by a shaft extending transversely through the figure and rotatable about said figure, an actuating member reciprocable transversely of said shaft within the figure, and means including a Scotch yoke mechanism connecting said actuating member and said shaft within the figure and operable to rotate the shaft and member during reciprocation of the actuating member.

5. In a mechanical toy, the combination of a figure, means supporting said figure for vertical reciprocation to simulate a jumping motion, a rotary shaft within the figure, a member driven by said shaft and representing a skipping rope

rotatable about the figure externally thereof, and means including a manually operable reciprocating member having an operative connection with said shaft within the figure and operable to rotate said shaft and reciprocate said figure in timed relation.

6. In a mechanical toy, the combination of a figure, a rotary mechanical driven member representing a skipping rope and rotatable about the figure, said rope comprising separated parts spaced apart at the center of the rope, and means including a manually operable reciprocating member for rotating said driven member.

10 7. In a toy of the type described, the combination of a vertically reciprocable figure, jointed arms loosely pivoted on the shoulders of the figure, a horizontal shaft rotatable in and extending transversely through the lower ends 20 of said arms and said figure, the latter being vertically slotted in the side walls thereof to receive said shaft, means on the outer ends of said shaft simulating a skipping rope, and means for rotating said driven member and vertically reciprocating the figure in timed relation whereby to turn said rope and flex said arms.

15 8. In a mechanical toy the combination of a figure, means including a stationary support projecting upwardly beneath the figure and supporting the same for vertical reciprocation, legs loosely pivoted on the lower portion of the figure and depending therefrom alongside said support, and means including cooperating abutments on said support and said legs for oscillating the legs 25 to simulate a skipping motion upon reciprocation of the figure with respect to said support.

30 9. In a mechanical toy the combination of a girl's figure having a skirt thereon, a stationary vertical supporting member projecting upwardly 40 into the interior of said skirt, means for reciprocating the figure on said support, a pair of legs projecting downwardly below said skirt, means pivotally supporting said legs, and means including cooperating abutments on said support and 45 on said legs for causing the latter to swing with respect to the figure upon reciprocation of the latter.

35 10. In a mechanical toy of the type described, the combination of an upright stationary supporting member, a figure, means guiding said figure for vertical reciprocatory movement on said support, a rotary mechanical driven member representing a skipping rope and rotatable about the figure, a pair of legs pivoted to swing loosely beneath the figure, and means including 50 cooperating abutments on said support and said legs arranged for alternative engagement and disengagement during the reciprocation of said figure for swinging said legs in timed relation with the figure reciprocation, and means for rotating said driven member and reciprocating the figure in timed relation.

55 11. A mechanical toy of the type described comprising, in combination, a base having an upstanding support thereon, a figure vertically reciprocable on said upstanding support, a rotary mechanically driven member representing a skipping rope and rotatable about the figure, an actuator finger piece on the base, and means 60 operable in response to periodic depressions of said finger piece for reciprocating the figure and rotating said driven member in timed relation.

70 12. A mechanical toy of the type described comprising, in combination, an elongated hollow base, a supporting upright fixed near one end

portion of the base, a figure guided for vertical reciprocation on said support, a rotary mechanical driven member representing a skipping rope and rotatable about the figure, means including a vertically reciprocable actuator bar projecting upwardly into the interior of the figure alongside said supporting upright for reciprocating the figure and rotating said driven member, a second actuator bar enclosed within said base and pivotally connected thereto at the end remote from said supporting upright, the free end of said second actuator bar being connected to the lower end of the first mentioned actuator bar, said base being apertured intermediate the ends of the second actuator bar, and a finger piece projecting through the base aperture for engagement by a user to depress periodically the second actuator bar and thereby reciprocate the first mentioned actuator bar.

13. A toy of the character described having, in combination, two vertical bars disposed side by side, one being stationary and the other reciprocable, a toy figure supported by said one of said bars and having legs hanging downwardly on opposite sides of said bars, a shaft extending horizontally through said figure, means operable during reciprocation of said reciprocable member to rotate said shaft, a simulated skipping rope comprising members projecting laterally from the ends of said shaft and then reversely toward each other to position their ends in substantial alinement and immediately adjacent opposite sides of said bars when the members are hanging downwardly, the members being of sufficient length to pass over the head of said figure and beneath said legs during rotation of said shaft.

14. A toy of the character described having, in combination, a vertical bar, a toy figure supported by said bar and having legs hanging downwardly on opposite sides of said bar, a rotary shaft extending horizontally through said figure, a simulated skipping rope comprising members projecting laterally from the ends of said shaft and then reversely toward each other to position their ends in substantial alinement and immediately adjacent opposite sides of said bar when the members are hanging downwardly, the members being of sufficient length to pass over the head of said figure and beneath said legs during rotation of said shaft.

15. A toy of the character described having, in

combination, a hollow toy figure, a member supporting said figure and projecting upwardly into the figure, means for reciprocating said member vertically, means extending through said figure and providing a simulated skipping rope, and means within said figure operable during reciprocation of said member to rotate said rope and alternately raise and lower said figure.

16. A toy of the character described having, in combination, a hollow toy figure, a member projecting upwardly into the figure, means for reciprocating said member vertically, means extending through said figure and providing a simulated skipping rope, and means within said figure and operable during reciprocation of said member to rotate said rope.

17. A toy having an articulated rotary member, a reciprocatory actuating member having a Scotch yoke connection with said rotary member, and manually operable means depressible periodically to move said actuating member in one direction and cause said rotary member to turn through a half revolution, the accumulated momentum of the parts carrying the rotary member through the remainder of the revolution whereby the speed of rotation of the rotary member is controlled by the periodicity of depression of the manually operable means.

18. A toy comprising a hollow figure having an articulated rotary member, a reciprocatory actuating member within said figure, means within said figure converting reciprocatory motion of said actuating member into rotary motion of said rotary member, and manually operable means depressible periodically to move said actuating member in one direction and cause said rotary member to turn through successive revolutions.

19. A toy of the character described having, in combination, an upright post, a hollow toy figure mounted on said post for vertical reciprocation, a member projecting upwardly into said figure and reciprocable along said post, means for reciprocating said member vertically, means extending through said figure and providing a simulated skipping rope, and means within said figure operable during reciprocation of said member to convert the reciprocatory motion of the member into rotary motion of said rope.

ARTHUR W. SWENSON.
